HYDRAULIC DRIVE FOR PUMPS OR
COMPRESSORS

Wilhelm Wirth, Berlin-Siemensstadt, Germany,
assignor to Patentverwertungs-Gesellschaft mit
beschränkter Haftung "Hermes," Berlin, Ger-
many, a corporation of Germany

Application August 9, 1939, Serial No. 289,169
In Germany June 3, 1938

4 Claims. (Cl. 230—49)

This invention relates to a hydraulic drive for pumps or compressors, particularly for compressors of refrigerating apparatus. It is known in the art that the working chamber of pumps of the above indicated character consists of two movable walls. The volume of the working chamber is alternately increased and reduced by a liquid set in motion by any suitable driving device. To avoid when using such indirect hydraulic drives the whirling caused by the motion of the liquid and the resistance to flow to a considerable extent and in order to firmly secure those parts of the compressor or the pump to which are connected the suction conduit and pressure conduit to the housing of the refrigerating apparatus it is known in the art to design the driving device for the driving liquid in such a manner that one portion of the liquid surrounding the compressor escapes upon each compression stroke of the compressor in the direction in which the movable walls move when being compressed and flows back in the opposite direction upon each expansion stroke of the compressor. In compressors consisting only of two movable walls opposite to each other the drive is so designed that during the compression stroke a certain amount of the liquid surrounding the compressor is pressed against one movable wall of the compressor and at the same time a certain smaller quantity of liquid is drawn away from the opposite wall of the compressor. During the expansion stroke the corresponding quantity of liquid is then drawn away from the first-mentioned wall of the compressor and the corresponding smaller amount of liquid is again pressed against the other wall of the compressor.

The invention relates to a drive of the last-mentioned type. The tank enclosing the pump or the compressor and containing the driving liquid is moved in an up- and downward direction by the driving device. In this manner it is possible to prevent particularly at the edge of the compressor walls the formation of a whirling motion in the driving liquid with the aid of very simple means. The arrangement is preferably so designed according to the invention that one wall of the tank containing the driving liquid is supported on the stationary holder of the pump or compressor, in which are arranged the suction conduit and pressure conduit, and that a connecting rod of the driving device is in engagement with the opposite wall of the tank containing the driving liquid.

In the accompanying drawing, comprising a single figure, there is shown an embodiment of

the invention in diagrammatic form. 1 and 2 denote two resilient walls of a compressor. These walls are secured to each other by a metal strip 3 bent around the edges of the walls 1 and 2 and enclose the working chamber 4 which in operation is alternately increased or reduced. The central portion of the movable wall 2 is secured to a holder 5 in which are arranged the suction conduit 6 and the pressure conduit 7 provided with the corresponding valves. The compressor is driven by a liquid, for instance, oil contained in the tank 8. This tank is moved according to the invention in the up- and downward direction by a crank drive. To this end, the connecting rod 10 of the crank drive is in engagement with the wall 9 of the tank. The opposite wall of the movable tank 11 is supported on the holder 5 of the compressor.

The tank 8 is so supported that the flange 12 of the wall 11 in contact with the holder 5 is slideable on the outer surface of the holder 5 in the upward and downward direction. On the pressure stroke, the receptacle or tank 8 is moved downwardly, and the liquid which is above the movable wall 1 is pressed against this wall. At the same time the pressure of the liquid underneath the movable wall 2 against this wall is relieved. Accordingly, both walls are moved in a downward direction and their curvature is reduced, which reduces the volume of the working chamber 4. On the suction stroke, the tank 8 is moved upwardly, the liquid pressures are reversed, and a movement of the walls 1 and 2 is produced, which expands the working chamber 4. The alternate contraction and expansion of the working chamber which is thus effected results in the desired circulation of the refrigerant through the conduits 6 and 7.

By proper selection of the ratio of diameter d_1 of the working chamber 4 to the diameter d_2 of the holder 5, the volume of liquid which is moved downward away from wall 2 on the pressure stroke can be made equal to the volume of liquid which is moved toward said wall on the suction stroke, and consequently during the operation of the pump no liquid will be transferred from that part of the tank which is below the working chamber to the part which lies above it, or vice versa. Since all flow of liquid around the periphery of the working chamber is thus prevented, the losses which formerly were incurred as the result of such currents in the liquid are avoided.

The invention having been described, that which is believed to be new and for which the

protection of Letters Patent is desired will be pointed out in the appended claims.

What is claimed is:

1. In a compressor type pump, two flexible walls secured together to form an expansible and contractible working chamber between them, inlet and outlet pipes communicating with said chamber, a tank surrounding said chamber, said tank having rigidly connected spaced walls which are parallel to the plane of said working chamber, a liquid filling said tank, said liquid being in direct contact with said walls, and means for giving said tank a reciprocating motion to create liquid pressures against said flexible walls which contract and expand said chamber.

2. In a compressor type pump, two flexible walls secured together to form an expansible and contractible working chamber between them, a support for one of said walls, inlet and outlet conduits extending through said support to said chamber, a tank surrounding said working chamber and having one wall which is slidable on said support, a liquid filling for said tank, said liquid being in direct contact with said walls, and means for imparting a reciprocating motion to said tank.

3. In a compressor type pump, a pump chamber comprising two flexible diaphragms secured together at their periphery, a centrally located support for one of said diaphragms, inlet and outlet conduits extending through said support to said chamber, valves controlling flow through said conduits, a tank surrounding said pump chamber and having two rigidly connected parallel walls, one of which has a sliding connection with said support, a liquid filling said tank, said liquid being in direct contact with said diaphragms, and means secured to the other of said walls for giving the tank a reciprocating motion.

4. In a compressor type pump, a liquid filled tank having two parallel spaced walls rigidly connected together, means for giving said tank a reciprocating motion along a line perpendicular to said walls, an expansible and contractible compressor inside said tank and surrounded by the liquid therein, said compressor having flexible walls in direct contact with said liquid, a fixed support for said compressor extending through one of the walls of said tank, and a liquid tight sliding connection between said support and said last mentioned wall.

WILHELM WIRTH.
